UNITED STATES PATENT OFFICE.

EDWIN N. GREEN, OF SYRACUSE, NEW YORK.

ELECTROTYPE-BLOCK-TRIMMING MACHINE.

1,217,297.

Specification of Letters Patent. Patented Feb. 27, 1917.

Application filed July 8, 1912. Serial No. 708,222.

To all whom it may concern:

Be it known that I, EDWIN N. GREEN, of Syracuse, in the county of Onondaga and State of New York, have invented a certain 5 new and useful Electrotype-Block-Trimming Machine, of which the following is a specification.

This invention relates to machines for trimming the bases of printing plates, to the 10 standard or desired height when such plates are too high or too low or are warped; and the invention consists in the combinations and constructions hereinafter set forth and claimed.

15 In describing this invention reference is had to the accompanying drawings in which like characters designate corresponding parts in all the views.

Figure 1 is a plan of my machine.

20 Fig. 2 is a sectional view on line "A—A" Fig. 1.

Fig. 3 is an enlarged sectional view, parts being removed on line "B—B", Fig. 2.

25 Fig. 4 is a detail view, partly broken away, of the clamping means for holding the block on the bed.

Fig. 5 is a detail view illustrating the opposing centers of the means for holding the block on the bed.

30 Fig. 6 is a diagrammatic view illustrating the inclination of the axis of the cutter head.

This machine for trimming the wooden blocks and metal bases of printing plates comprises, generally, a frame, a bed and 35 planing means supported by the frame and having relative feeding movement, means for actuating the planing means and for effecting the relative feeding movement of the planing means and the bed, and means for 40 holding the block to be trimmed on the bed whereby the block after having been planed and removed can be again replaced in the holding means in exactly the same position previously occupied and again trimmed if 45 additional trimming is necessary.

1 is the base of the frame, the base having feet 2 by which it can be attached to the pressman's bench, and being formed with ways 3. 4 are uprights at opposite sides of 50 the base, and 5 is a bridge or strut connecting the uprights and supporting a central bearing composed of two sections 6 spaced apart.

7 is the bed for supporting the blocks as 8, 55 the bed being here shown as movable along

the ways 3 relatively to the planing head 9, which is here shown as rotatable and having a spindle 10 journaled in a sleeve 11 in the bearing 6, the head 9 carrying a planing knife 12. The axis of the bearing 6 and 60 spindle 10 is inclined slightly toward the bed 1 out of a vertical line. This inclination is very slight as illustrated in Fig. 6 and is in such direction that the knife 12 is at its lowest level when cutting. The inclination is, 65 however, so slight that the knife 12 sweeps across the block in the horizontal line so as to remove the layer of equal width throughout and not a layer which is appreciably thicker at its center, which would be the 70 case if the inclination were greater.

13 is a driving wheel journaled in a bearing supported by the base 1 of the frame and connected to the spindle 10 to rotate the same, and also to the bed 7 to feed the bed. 75

In the illustrated form of my invention, the power-transmitting means between the driving wheel and the spindle comprises an endless belt 14 movable around the periphery of the wheel 13 and around pulleys 15 80 supported by one of the uprights 4 of the frame and around a pulley 16 at the upper end of the spindle.

The head 9 is movable axially by means of a hand-operated internally-threaded adjusting wheel 17 located between the sections of the bearing 6 and coaxing with the externally-threaded surface of the sleeve 11, the sleeve 11 being movable axially with the spindle 10. 85

The lower end of the bearing 6 is split and clamped to fit, without binding on and also without being loose on, the sleeve 11 by a suitable screw passing through lugs, as the lug 6¹, on opposite sides of the line of division of the bearing 6. 95

The power-transmitting means, here illustrated, between the driving wheel 13 and the bed 7 comprises a belt 18 running on a pulley 19 arranged concentrically with the wheel 13 and around pulleys 20 supported by the frame near one end thereof and over the pulley 21 mounted on the rotating screw 22 journaled in the frame and coaxing with a split nut 23 movable with the bed 7. 100

As seen in Fig. 3, the sections of the split nut 23 are pivoted at 24 and are normally held apart by a spring 25 and are movable together to engage the screw by the head member 26 suitably connected to the sec- 110

tions of the split nut to operate the same. The bed is fed toward the cutter or knife by the screw 22 and is drawn outwardly by hand after the sections of the split nut have 5 been separated. The head 26 is in the form of a wedge which enters between and separates arms 23^a of the split nut and hence closes the split nut against the action of its spring 25. The head is carried by a rod 26^a 10 slideable lengthwise of the bed 3 beneath the same, the rod being movable with the bed and having a handle 26^b, Fig. 1.

The means for holding the blocks on the bed whereby the block after having been 15 once planed and removed can again be replaced in the holding means in exactly the same position previously occupied comprises elements 27, 28 extending crosswise of the bed, one element as 27 being fixed to the bed 20 and the other shiftable relatively thereto toward and from the element 27, and pairs of centers 29, 30 carried respectively by the elements 27, 28, the centers on the element 27 being fixed and those on the element 28 being 25 here shown as screws and the points of the centers being conical.

The means for holding the shiftable clamping element from movement relatively to the bed, after having been set in position 30 comprises clamping members 31 arranged on opposite sides of the bed 7 and engaging the ends of the member 28, and a single operating part for operating the members 31. Said members are here shown as formed 35 with overhanging shoulders 32, Fig. 3, for engaging the shoulders 33 projecting from the end of said member 28, and is also formed with inclined cam slots 34, Fig. 4, at intervals through which fixed pins 35 40 project, such pins extending into the opposite side edges of the bed 7.

The operating part is located at the outer end of the bed 7 and is here shown as a rock shaft 36 having eccentrics 37 at its opposite 45 ends which work in slots 38 at the outer ends of the clamping members 31.

As the shaft 36 is operated the members 31 will be moved endwise and owing to the cam slots 34 and pins 35 will be moved 50 downwardly to clamp the member 28 on the face of the bed when the handle 40 on the shaft 36 is swung outwardly or to the right, Fig. 4, and will release said member 28 when the handle is swung in the opposite direction. The handle 40 is in the form of a 55 rock arm having a knob at its outer end.

The blocks of printing plates as electro- 60 types, vignette cuts, etc., become warped or otherwise defective and hence will rock when placed in the printing form and must be trimmed so that they will set type high in the form, and often the plates must be 65 reblocked, an operation which has heretofore been performed by the electrotyper and which necessitates sending the block to an

electrotyper. By my invention all trimming can be accurately done by the pressman in a very short time.

My machine is particularly advantageous for trimming vignette and half-tone cuts, 70 as such cuts have to be less than type high on the bed of the printing press in order to allow for the overlay placed on the cylinder of the press, as will be understood by those skilled in the art, and it still further 75 has to be lowered if the cut is innerlaid between its copper plate and the block, which is almost invariably the case; and further, after the vignette has been innerlaid, owing 80 to the convexity of the printing surface thereof, it is necessary to reduce the thickness or height of the block by taking off an even shaving from the back thereof.

In trimming such vignette cuts in my machine, paper sheets of the thicknesses 85 of the overlay of the cylinder and the innerlaid of the cut are placed on the bed of my machine, the cut placed face down, the clamping means placed contiguous to the cut, the finger screws or centers 30 turned 90 to make indentations in opposite edges of the block so as to hold the block in the machine, the knife adjusted to type high by means of the adjuster 17, and the machine operated to take off a thin shaving from the 95 entire rear face of the block. After the shaving operation, if it is necessary to additionally innerlaid the cut, it is necessary to additionally trim the block, and a sheet of paper corresponding to the thickness of the additional innerlaid is taken off the bed 100 of the machine and the cut placed back on the bed with the finger screws or centers in the same indentations as before, and the planing operation repeated.

It will thus be seen that the finger screws or centers guide the block to the same position as it previously occupied, thus avoiding tipping of the block, and, consequently, the planing off of an uneven layer. A suitable shield 41 is provided for preventing 110 the shavings from flying, this shield being pivoted at its opposite ends and being movable upwardly on its pivot into engagement with the latch 42, Fig. 2, when it is desired 115 to inspect the portion of the block being cut.

My machine is particularly advantageous in that the pressman can trim accurately or reblock his printing plates or electrotypes 120 in a short time. In fact, any block can be properly trimmed in less than two minutes. Owing to the arrangement of the centers 29, 30 the blocks can be always placed in the machine at the position previously occupied 125 so that the type high position is readily determined.

What I claim is:

1. In a machine for trimming the blocks of printing plates, the combination with a 130

- bed for supporting the blocks, planing means having relative feeding movement, of means for holding the block on the bed, said means being operable to reposition the block 5 after having been operated on and removed, in the exact position previously occupied, comprising opposing sets or points, members for holding said points, one member being adjustable bodily toward and from the other, 10 and the points being adjustable individually relatively to said members, and means for holding the adjustable member in its adjusted position, substantially as and for the purpose set forth.
- 15 2. In a machine for trimming the blocks of printing plates, the combination with a bed for supporting the blocks and planing means having relative feeding movement, of means for holding the blocks on the bed, 20 comprising supporting elements mounted on the bed, one element being shiftable lengthwise of the bed, a plurality of pairs of opposing centers carried by said elements for engaging opposite edges of the blocks, and 25 means for clamping the shiftable element on the face of the bed, substantially as and for the purpose described.
3. In a machine for trimming the blocks of printing plates, the combination with a 30 bed for supporting the blocks and planing means having relative feeding movement, of means for holding the blocks on the bed comprising supporting elements mounted on the bed, one element being shiftable length- 35 wise of the bed, a plurality of pairs of opposing centers carried by said elements for engaging the opposite edges of the block, and means for clamping the shiftable element to the face of the bed, the clamping 40 means comprising members located at opposite sides of the bed for coacting with opposite ends of the members, and a single operating part located at one end of the bed for said members, substantially as and 45 for the purpose specified.
4. A machine for trimming the blocks of printing plates, the combination with a bed for supporting the blocks and planing means having relative feeding movement, of means 50 for holding the block in the bed comprising supporting elements mounted on the bed, one element being shiftable lengthwise of the bed, a plurality of pairs of opposing centers for engaging the opposite edges of 55 the block carried by the elements, and means for clamping the shiftable element to the face of the bed, the clamping means comprising members coacting with opposite ends of said element and having cam slots at in- 60 tervals, and being movable lengthwise of the bed, fixed pins extending through the slots and into the side edges of the bed, and means for moving said members lengthwise comprising a rotary part located at one end of the bed and having eccentric pins at its 65 opposite ends coacting with said members, substantially as and for the purpose set forth.
5. In a machine for trimming the blocks of printing plates, the combination with a 70 bed for supporting the blocks and planing means having relative feeding movement, of means for holding the block in the bed, comprising supporting elements mounted on the bed, one element being movable lengthwise 75 of the bed, a plurality of pairs of opposing centers carried by said elements for engaging opposite edges of the block, the shiftable element having shoulders projecting from its ends, clamping members located on 80 opposite sides of the bed and having overhanging shoulders for coacting with the shoulders of said element, the clamping members being formed with cam slots, fixed pins extending through the cam slots into 85 the edges of the bed and an operating part for the clamping members, said part being located at one end of the bed and being movable about an axis and having eccentrics at its opposite ends for coacting with said 90 members to move the same endwise, substantially as and for the purpose described.
6. In a machine for trimming blocks, the combination of a bed for supporting the blocks, and planing means having relative 95 feeding movement one toward and from the other in the direction of the face of the bed, the planing means, including a rotating head having a cutter located near the outer margin of the head and being spaced apart from the axis of the head whereby the cutter removes a narrow shaving, the head being arranged with its axis inclined out of a line perpendicular to the direction of the feeding movement, whereby the face of the block 100 is slightly concaved with the corners thereof high upon which the block may rest when placed in a printing press, substantially as and for the purpose specified.
- 105 In testimony whereof, I have hereunto signed my name in the presence of two attesting witnesses, at Syracuse, in the county of Onondaga, in the State of New York, this 22nd day of April, 1912.
